UNITED STATES PATENT OFFICE.

WILLIAM P. HALL, OF PIQUA, OHIO.

IMPROVEMENT IN STEAM-BOILER CASINGS AND FURNACES.

Specification forming part of Letters Patent No. 122,010, dated December 19, 1871.

To all whom it may concern:

Be it known that I, WILLIAM P. HALL, of Piqua, in the county of Miami and in the State of Ohio, have invented certain new and useful Improvements in Steam-Boiler Casing and Furnace; and do hereby declare that the following is a full, clear, and exact description thereof, reference being had to the accompanying drawing and to the letters of reference marked thereon making a part of this specification.

The nature of my invention consists in the construction and arrangement of a steam-boiler casing, and also of a furnace, as will be hereinafter more fully set forth.

In order to enable others skilled in the art to which my invention appertains to make and use the same, I will now proceed to describe its construction and operation, referring to the annexed drawing, in which—

Figure 1 is a front end view, with the front wall removed; and Fig. 2 is a longitudinal vertical section of my steam-boiler casing and furnace. Fig. 3 is a side view of an exterior air-receiver used with my furnace. Fig. 4 is a rear end view of my steam-boiler casing, with the rear wall removed.

A represents a horizontal return-flue steam-boiler, which is placed within a brick casing, B, entirely surrounding the boiler. This casing B is, at the front end, of just such interior diameter that the boiler, or rather the front end of the boiler, will entirely fill the same, while immediately back of the front end and its entire length rearward the interior diameter of the casing is so much larger than that of the boiler that the flames and heat will have free play around all sides of the boiler. The boiler and casing are further so arranged that the space between them at the bottom will be larger than at the top, as more particularly shown in Fig. 4. The interior of the casing B, as well as the boiler, are true circles; but the boiler is supported upon feet C C, so as to be out of the center of the casing and thus give the inequality in the space between them, as mentioned above. In the front end of the casing B, below the boiler, are the furnaces D D, constructed as will be hereinafter described. The flames, smoke, &c., from these furnaces pass up under the boiler B, completely enveloping the same, and enter a circular recess, a, in the rear wall E, said recess corresponding with the inter-

ior of the casing; and from thence the smoke, heat, &c., pass forward through the flues of the boiler into a similar recess, a', in the front wall E', and from thence up through the chimney G. By this means the entire surface of the boiler is made a heating-surface, not only the bottom and through the flues, as is usually the case, but also the top and ends of the same. The space below the boiler being larger than that above, equalizes the heat on all parts of the boiler, as the tendency of heat is to rise, and the excess of space below the boiler gives room for more of the flames to go through there than at the sides or top. The front and back walls E E' are provided with suitable doors for cleaning out the flues of the boiler. To prevent radiation of heat from the sides and top of the casing B, I surround the same with a sheet-metal cap or covering, H, leaving a suitable space between the two, which space is to be filled with ashes or other convenient non-conducting material. The furnaces D D, at the front end of the casing under the boiler, are each provided with an air-chamber, b, around the sides and top, as shown in Fig. 1, said furnaces being in arch form. From these air-chambers small apertures i i lead into the space below the boiler directly at or above the point where the flames, smoke, &c., from the furnaces enter said space, for the purpose of admitting jets of air to aid in combustion. In place of jets of air a complete sheet of air may be admitted by a narrow continuous opening instead of the apertures i i; but I prefer said apertures, as thereby the strength of the brick-work need not be diminished. On the outside of each furnace is placed an air-receiver, I, into which air is forced by a fan or blower, and from which the air is forced, through a tube, d, into the ash pit under the furnace so as to come up through the grate. Another tube, e, leads from the exterior air-receiver I to the air-chamber b, so that the air may be forced into said air-chamber, and, through the apertures i i, into the casing, for the purposes above mentioned.

I do not intend to confine myself to the use of these furnaces with my steam-boiler casing, as any furnace may be used with the casing, and my furnace may be used for every purpose where a furnace is needed.

The amount of air admitted into the air-chambers b b from the exterior air-receivers I I may be regulated by a damper, f, in the tube e.

Having thus fully described my invention, what I claim as new, and desire to secure by Letters Patent, is—

1. The horizontal return-flue boiler A within the casing B, with a hot-air space between all sides and ends of the boiler and the casing to allow the heat to entirely envelop the boiler, substantially as set forth.

2. The combination, with the casing B, boiler A, and surrounding chamber, of the end walls E', provided with inner recesses $a a'$, of a diameter larger than that of the boiler, substantially as and for the purposes herein set forth.

3. The combination, with the casing B and its

elongated chamber, of the boiler A and the notched or perforated supports C between the boiler and bottom of the chamber, substantially as and for the purposes herein set forth.

4. The combination of the furnace D, air-chamber b with apertures $i i$, exterior air-receiver I, and tubes $d e$, all constructed and arranged substantially as and for the purposes herein set forth.

In testimony that I claim the foregoing I have hereunto set my hand this 9th day of October, 1871.

Witnesses:
